CLAIM

The ornamental design for a medical waste disposal bin, as shown and described herein.

DESCRIPTION

FIG. 1 is an upper, exploded perspective view of a medical waste disposal bin showing our new design;

FIG. 2 is an upper perspective view of the medical waste disposal bin with its lid coupled to its base;

FIG. 3 is an upper perspective view of the medical waste disposal bin with its lid in an open configuration;

FIG. 4 is an upper, exploded perspective view of the medical waste disposal bin shown from the opposite side relative to that of FIG. 1;

FIG. 5 is an upper perspective view thereof from the opposite side relative to that of FIG. 2;

FIG. 6 is a lower, exploded perspective view of the medical waste disposal bin;

FIG. 7 is a lower perspective view thereof;

FIG. 8 is a rear elevation view thereof;

FIG. 9 is a front elevation view thereof;

FIG. 10 is a first side elevation view thereof;

FIG. 11 is a second side elevation view thereof opposite from the first side depicted in FIG. 10;

FIG. 12 is a top plan view thereof; and,

FIG. 13 is a bottom plan view thereof.

The portions of the drawings shown in broken lines form no part of the claimed design.
